CHRISTOPHER OSTRANDER, OF LODI, WISCONSIN.

Letters Patent No. 98,185, dated December 21, 1869.

IMPROVEMENT IN FARM-GATES.

The Schedule referred to in these Letters Patent and making part of the same.

To all whom it may concern:

Be it known that I, CHRISTOPHER OSTRANDER, of Lodi, in the county of Columbia, and State of Wisconsin, have invented certain new and useful Improvements in Farm-Gates; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to gates; and

It consists in certain improvements upon that class of farm-gates which is opened by sliding them back a portion of their length, and then swinging them around.

In the drawing—

Figure 1 is a side elevation of my gate, closed, and

Figure 2 is a top plan view of the same, open, a portion of the top rail being broken away to show other parts more clearly, and the position of the gate when closed, shown by dotted lines.

A' are the gate-posts, the former having secured to it a projecting arm or bracket, a, provided at its outer end with a vertical hole.

B is a metallic swivelling head, mounted on and having a stem fitting into the hole in arm a.

This head B, I cast of metal, in a single piece, and of the form shown, and place in it two rollers, c c, whose journals have bearings between the arms b b of the walls of the head.

In the head, below the rollers c c, I make openings down through, so that snow, dirt, water, &c, getting into it, will escape through these openings, instead of impeding the action of the rollers, especially in the winter-season.

C is the gate, having its front bar j extended below the bottom rail, and having pivoted in its lower end a roller, E, as shown in fig. 1.

This gate C, I place with the back end of its top rail d resting in head B upon the rollers c c, the arms b b serving to guide the rail, and keep it upon the rollers, as shown in figs. 1 and 2.

When thus arranged, the head B supports the rear, and the roller E the front end of the gate, at the proper height, and off from the ground.

To close the gate, it is only necessary to apply sufficient power to slide the gate up to post A, and not,

as with the ordinary gates, to support the front end by hand.

To open the gate, it is slid back until it balances upon the rollers c c, and the roller E rises from the ground, and it is then turned around, upon the swivelled head, to the position shown in fig. 2.

To prevent accidental displacement of the gate from the head B, I drive into the post A, above the top rail d, a pin or peg, k, and also drive into the earth, outside of the gate, opposite the corner of post A, a stake, e, as shown in figs. 1 and 2.

To aid in opening the gate quickly, I secure on the gate the vertical bar m, in such position that when the gate has run back the proper distance to balance, the bar will strike against the head B, and prevent further longitudinal movement of the gate, which may be run back quickly, and not be liable to pass the balancing point, as would occur were it not for this bar or strip.

F is a catch, passing lengthwise through the front of the gate, and pivoted at o, the inner end being made to overbalance the outer, and the outer end having formed on its upper side a bevelled catch or head, g.

To secure the gate by this catch, it is only necessary to close it, when the outer end of the catch enters a mortise made through post A' for the purpose, and its head g, projecting through, engages over the outer edge of said mortise, and thus prevents the gate from being drawn back.

The gate is released by lifting the inner end of catch or lever F, which disengages the head g.

h is an arm or block, secured to the front end of the gate, immediately below the latch F, and which, when the gate is closed, enters the mortise with the catch, thus relieving it from lateral strain, which would cause it to bind in the mortise, and render its disengagement difficult.

This gate is strong, cheap, and efficient, can be operated by a small child, and is not liable to injury by snow or ice.

Having thus described my invention,
What I claim, is—

The gate C, hung on the two rollers c c, mounted in a swivelled case, B, and provided with roller E and pivoted latch F, to engage in post A, all constructed and arranged as herein described.

Witnesses: CHRISTOPHER OSTRANDER.
